UNITED STATES PATENT OFFICE.

JOHN B. JONES, OF ATLANTIC CITY, NEW JERSEY.

SEPARATING MATERIAL FOR MOLDS.

1,406,651.

Specification of Letters Patent. Patented Feb. 14, 1922.

No Drawing.

Application filed December 24, 1920. Serial No. 433,031.

To all whom it may concern:

Be it known that I, JOHN B. JONES, a citizen of the United States, and resident of Atlantic City, in the county of Atlantic and

5 State of New Jersey, have invented certain new and useful Improvements in Separating Materials for Molds, of which the following is a specification.

My invention relates to molds adapted to 10 be used by dentists and others, and pertains more particularly to materials for application to the surface of the mold to facilitate separation of the cast therefrom.

As is well known, plaster of Paris, cement, 15 concrete, and like materials are used in casting, in many instances for both the mold and the cast formed therein. Plaster of Paris is commonly used by dentists for taking an impression of the teeth and interior of the 20 mouth and for forming the mold in which the cast is made, the cast material also generally being plaster of Paris or some similar material. Due to the fact that the mold and cast materials are of the same nature and pos- 25 sessed of rapid-hardening qualities, consider- able difficulty has been experienced in sepa- rating the mold from the cast after the casting operation, without injury to the latter. Similar trouble has been found in the use 30 of molds of cement, concrete and like mate- rials used for other purposes, it being often- times necessary to cut or chip the mold away from the cast, with the result that the mold is destroyed and the cast exposed to the danger 35 of injury by the cutting operation.

To render it possible to separate the mold from the cast more readily and enable the mold to be used repeatedly the surface of the mold has been coated with various mate- 40 rials designed to present a well-defined line of demarcation between the mold and the cast and to render the surface of the mold smooth, so that the material of the cast might not adhere thereto, but be easily separable 45 therefrom after the cast material had set.

One method hitherto employed was to apply to the interior surface of the mold a coating of oil, usually superposed upon a coat of shellac or other substance. This proc- 50 ess required two distinct applications of sepa- rating materials, and since the oil coating could not be applied until the shellac was thoroughly dry and hard, its use involved more time than where a single coat is ap- plied and thus delayed the casting operation.

The coat of oil is not only inconvenient, but is also disagreeable to the operator, being sticky or gummy and soiling both the cast and the hands of the operator or user.

Other materials have been used, principally in alcoholic solution, but these are unsatisfactory on account of the present high cost of alcohol and for the reason that alcohol evaporates so rapidly that a separator material containing it cannot be handled so 60 conveniently and will not retain its original condition or consistency for so long a period as a material in which no alcohol or other rapidly-evaporating agent is present.

The objects of my invention are to over- 65 come these disadvantages and provide a sepa- rating material that is convenient to handle and easy to prepare and apply, that can be produced at comparatively low cost without the use of alcohol or similar agents, that is 70 not sticky and will not injuriously affect either the mold or cast or the hands of the user, that will retain its proper or desired condition more satisfactorily and for a longer time than materials containing alco- 75 hol, ether, or other highly volatile agents, and that will permit the cast to be easily and quickly separated from the mold.

The composition I employ to attain these 80 beneficial results consists of shellac in an al-kaline solution; the alkaline substance being preferably borax. In preparing the compo- sition, the borax and shellac are preferably powdered and mixed in the proper propor- 85 tions, in which condition they are in conven- ient form to be supplied to the trade. A mixture of approximately equal parts of borax and shellac gives good results, but the proportions may be varied somewhat. The preferred mixture consists of approximately 90 535 grains of borax and 580 grains of shel- lac.

To prepare the mixture for use, it is dis- 95 solved in clear hot water, preferably in the proportion of about two parts of the mixture 100 to ten parts of water, 1100 or 1200 grains of the mixture being dissolved in approxi- mately one pint of water. The water should not be boiling, but considerable latitude may be had in regard to the water temperature. 105 The mixture of borax and shellac is poured slowly into the hot water and stirred until all of the mixture is dissolved. By this process an aqueous solution of borax is ob- 110 tained, in which solution the shellac is dis-

solved to form an alkali salt of resin, in the nature of a resin soap.

When cool, the substance is ready for use and may be applied to the mold with a brush, 5 by immersion, or in any other convenient or suitable manner. The coating thus formed gives to the mold a smooth, hard surface, from which the material of the cast may be easily separated. If desired, the separating 10 substance may be bottled and, if securely corked, will retain its proper consistency indefinitely and may be used from time to time as needed.

Coloring matter may be added to the separating material at the option of the user, the 15 coloring of the coat laid on the surface of the mold serving to more clearly define the line between the mold and the cast. The use

of such coloring matter is, however, not essential and forms no part of my invention. 20

I claim:

1. A separating material for plaster casts and the like which consists of shellac dissolved in an aqueous solution of borax. 25

2. A separating material for plaster casts

and the like which comprises shellac, borax

and water, in approximately the proportions

of 535 grains of borax and 580 grains of

shellac to one pint of water.

3. A separating material for plaster casts 30 and the like which consists of approximately equal parts of borax and shellac dissolved in water.

In testimony whereof I affix my signature.

JOHN B. JONES.
